UNITED STATES PATENT OFFICE.

JOSEPH O. BULLARD, OF CAMBRIDGE, MASSACHUSETTS.

IMPROVEMENT IN MACHINES FOR MAKING FLOWER-POTS.

Specification forming part of Letters Patent No. 147,897, dated February 24, 1874; application filed January 22, 1874.

To all whom it may concern:

Be it known that I, JOSEPH O. BULLARD, of Cambridge, in the county of Middlesex and State of Massachusetts, have invented certain new and useful Improvements in Pot-Machines; and I do hereby declare the following to be a full, clear, and exact description of the invention, such as will enable others skilled in the art to which it pertains to make and use it, reference being had to the accompanying drawings, which form part of this specification.

My invention relates to improvements in machines for making flower-pots, consisting in the combination of a female mold and a rotary core-mold with a rotary top-mold, that is rotated by the friction between the upper side and the under side of the flange on the core-mold; also, in the combination, with a rotary core-mold, of an elastic center punch, for the purpose of making the hole in the bottom of the flower-pots, as will now be more fully shown and described.

On the drawing, Figure 1 represents a ground plan of my invention. Fig. 2 represents a sectional longitudinal elevation, and Fig. 3 represents an enlarged longitudinal section of the rotary core-mold and its frictional top-mold.

a represents the female mold, that is secured to a suitable support, *b*, as shown in Fig. 2. The support *b* is moved up and down in a vertical direction by means of the treadle-lever *c*, link *d*, crank *e*, rack *f*, and pinion *g*, or other well-known combination. The support *b* is made to slide in suitable guides on the standard *h*. The core-mold *i* is secured to a vertical shaft, *k*, that is set in a rotary motion by means of power applied to the pulley *l*. (Shown in Fig. 2.) The shaft *k* is supported in the bearings *m m'*, secured to the standard *h*. The core-mold *i* and its shaft *k* are moved up and down in a vertical direction by means of the lever *n*, hinged at *p*, and the connection *o*, hinged to the pinion *g*, or other well-known devices. The core-mold *i* is provided with an annular flange, *q*, covered on its under side with leather *s*, or suitable material. An annular ring, *r*, surrounds the core-mold *i*, and constitutes the top-mold, for the purpose of finishing off the top of the flower-pots. This top-mold *r* is loosely supported in a suitable stationary ring or bearing, *t*, secured to the

standard *h*, as shown, by means of guide-pins *u u*, or their equivalents. The top-mold *r* is provided, on its upper side, with a leather or other suitable frictional covering, *v*, for the purpose of increasing the friction between the under side of the flange *q* and the upper side of the top-mold *r* when they are brought in contact with each other. The object of the ring *r*, flange *q*, and their frictional coverings is for the purpose of rotating the ring *r* by friction when the core-mold *i*, which is rotating, is brought in contact with the upper side of the ring *r*, when the ring *r* partakes of the rotary motion of the core-mold *i*, by which arrangement I am able to finish the top of the flower-pots a great deal better than could be done with a stationary top-molder, as heretofore used.

The operation of my improved pot-machine is as follows: The pulley *l*, shaft *k*, and core-mold *i* are set in a rotary motion, as described, and a suitable quantity of clay is placed in the female mold *a*, as usual. The female mold *a* and the core-mold *i* are brought toward each other by means of the treadle *c*, link *d*, crank *e*, rack and pinion *f g*, connection *o*, and lever *n*, or their equivalents, as heretofore described, when the rotating mold *i*, in combination with the female mold *a*, forms the pot in the annular space between them. At the same time, as the female mold *a* is brought almost to its highest point, the flange *q* and its covering *s* come in contact with the covering *v* on the top-molder *r*, by which the said top-molder *r* is set in a rotary motion with the core-mold *i*, and thus turns and finishes off the top of the pot clean and even, without leaving a ragged edge, as heretofore has been the case where a stationary top-molder has been used.

w represents the ordinary rest in the mold *a*, by which the pot that is made in the mold is raised upward as soon as ready.

I am aware that a patent was granted to William Linton, dated February 12, 1861, and numbered 31,394, in which a yielding, but not rotary, top-mold is used, in combination with a rotary core-mold.

My elastic center punch *x*, Fig. 3, for the purpose of making the hole in the bottom of the pot is constructed as follows: I make a suitable recess in the center of the rotary core-

mold *i*, as shown, in which is placed a coiled spring, *y*, or its equivalent, resting against the bottom of the said recess, and against the head of the punch *x*. The punch *x* is movable up and down in a sleeve, *z*, that is fastened to the stuffing - box *z'* by means of a screw-thread or similar means. The space between the lower part of the sleeve *z* and the box *z'* is to be filled with suitable packing, for the purpose of preventing the clay from working up in the recess behind the punch *x*, thus insuring a free action of the spring *y*. The hole in the bottom of the pot is made by the punch *x* coming in contact with the rest or false bottom *w* in the female mold *a*, by which, and the yielding movement of the elastic punch *x*, a clean and proper hole is made through the bottom of the pot.

Having thus fully described the nature, con-

struction, and operation of my invention, I wish to secure by Letters Patent, and claim—

1. In combination with a rotary and traversing core-mold, *i*, and the female mold *a*, the rotary top - mold *r* and the frictional surfaces *s v*, as and for the purpose herein set forth and described.

2. In combination with the rotary core-mold *i*, the elastic punch *x*, spring *y*, stuffing-box *z'*, and its packing, as herein shown, and for the purpose set forth.

In testimony that I claim the foregoing I have hereunto set my hand this 12th day of January, 1874.

JOSEPH O. BULLARD.
